Inventor:

S. R. Krom.

UNITED STATES PATENT OFFICE.

S. R. KROM, OF NEW YORK, N. Y.

IMPROVED APPARATUS FOR CONCENTRATING ORES AND MINERALS.

Specification forming part of Letters Patent No. 80,747, dated August 4, 1868.

To all whom it may concern:

Be it known that I, S. R. KROM, of the city, county, and State of New York, have invented a new and useful Improvement in Ore Concentrators or Separators, or beds thereof, of which the following is a full, clear, and exact description, reference being had to the accompanying drawing, forming part of this specification, and in which—

Figure III represents a transverse section of an ore separating and concentrating machine, known as Krom's ore-separator, having the improved ore-bed herein described applied to it. Fig. IV is a similar view of the same machine, showing a modification of said bed. Fig. V is a view in perspective, on a larger scale, of the improved ore-bed according to one of its forms of construction. Fig. VI is a sectional elevation of the same, taken lengthwise of one of the tubes of which it is composed; Figs. VII and VIII, sectional views or elevations at right angles to each other; and Fig. IX a similar section to Fig. VII of the ore-bed under two different modifications of it.

Similar letters of reference indicate corresponding parts.

My invention consists in an ore-bed composed of tubes constructed and arranged to admit of the passage within and through, or out of them, of a current or currents of air or water in such manner as that said air or water in escaping therefrom will meet in the center, or cross the opening or openings in the bed through which the ore, or certain grades of it, descend or pass in being separated; also, said invention further consists in an ore-bed made up of tubes or hollow bars of reticulated character, for the passage of air or water through them, and made either of an open or closed character at their bottoms. By this my improvement, which relates to that description of ore-bed that admits of the heavy particles of ore falling through the opening or openings in the bed, for removal by suitable means, as thus passed or separated a free action of air or water is secured on the ore lying on the bed, and at the same time an unrestricted and convenient escape for the concentrated or rich ore established also, whereby a shorter bed-travel for the ore to be separated is required or rendered necessary.

The improvement, though shown in Figs. III

and IV as applied to an ore-separating machine of a special construction, and for which Letters Patent have been allowed me, is also applicable to other ore concentrators or separators, and no very special or minute reference need here be made to the feed of the ore for travel along or over the bed, or the means for producing the current or currents of air or water, and conducting the same to the bed; nor yet to the means for removing the rich ore as it is delivered from the bed. In these views, however, which illustrate how my improved ore-bed is or may be applied, the ore to be separated is represented as being delivered from a hopper onto or over the bed; also, the same exposed to the action of an intermittent current or currents produced by a bellows; likewise the timely removal of the rich ore escaping through the opening or openings in the bed as effected by a suitably constructed and operating roller below.

The ore-bed itself, which constitutes the improvement made the subject of this application, may be constructed as represented in Figs. III, V, and VI. This bed is made up of tubes or hollow bar-like divisions *a*, of any suitable shape, arranged within a suitable frame, so as to run in direction of the travel of the ore across the bed, that may be termed the length of the latter, and at a proper distance apart to establish passages *b* between them. These tubes are shown of a reticulated character, being made of wire-gauze or other suitable perforated material, and open at one end, as at *c*. The width of said bed, or length transversely to the travel of the ore across it, is considerably in excess of the length of the tubes. The distance apart of the tubes *a* may be varied to suit different kinds of ore, but should be sufficiently close together so that air or water forced into them through their mouths or open ends *c*, and escaping from or through the sides of the tubes, will readily meet in the centers of the passages *b*, and produce a uniform action throughout the same, no difference of action being perceptible in the application of said bed to a machine when the latter is running on the surface of the ore and the stratum of rich ore lying immediately on the bed and the stratum of lighter material lying on top being of uniform thickness throughout. As the tubes *a* are constructed in these figures—III, V, and

VI—the air or water forced in intermittently during, for instance, the upward movement of the bellows, escapes from said tubes, to effect the separation of the ore on three sides—that is, through the top and on either side.

In working, the ore in the passages or spaces *b* between the tubes is supported by resting on the column or columns of ore below, and sinks as fast as the means employed for removal effects discharge of the ore from the lower ends of the columns.

Wooden or other suitable bottoms *d* may be fitted within the perforated tubes *a*, and suitable holes made therethrough for the purpose of letting escape any fine ore that may fall through the meshes of the tubes.

In some cases, however—and it is preferred to make them so—the tubes *a* may be left entirely open below by dispensing with the wooden bottoms, as represented in Fig. VII, so that any fine ore entering the tubes will fall direct on the main columns below without any obstruction. Nor will the ore from the passages *b* or main columns rise under such an open construction of the bottoms of the tubes within the air or water space of the latter, but assume the shape or direction represented in Fig. VIII. Such open construction of the bottom of the tubes also admits of the air or water forced into them escaping laterally from beneath them as well as through them to act upon the ore.

One advantage, however, the closed bottom construction may have is, that the bottoms serve to stiffen and give solidity, as it were, to the tubes.

Where the tubes are left of a freely open character at their bottoms they may, if desired, not be made of gauze or otherwise reticulated, but of a close sheet construction, as shown in Figs. VIII and IX, being more or less of an inverted **U** form, in which case the air or water is caused wholly to pass laterally from beneath them, and up through the passages *b* between the tubes.

As a further modification of the bed, the same may be made with an opening or passage through it for the concentrated ore to pass through, in a right-angled direction to that hereinbefore described, namely, lengthwise of the machine or across the travel of the ore over the bed, as represented in Fig. IV, and the air or water be introduced to es-

cape through or laterally from beneath the one or both sides of the said opening to meet in the center of, or similarly act upon, the ore in said opening, substantially as hereinbefore described, and for which purpose the air or water may be admitted for escape up from beneath the one side of said opening by a bent tube or tubes, open at both ends, and arranged below the hollow bed, as shown in said Fig. IV.

By this my improved ore-bed I am enabled to effect a more perfect separation, and to concentrate in a shorter distance, expending the force employed on a greater width of ore-bed relatively to the travel of ore over it, instead of wasting it over a long ore-bed.

When drawing off the rich or concentrated ore in machines employing the old form of bed having a small extent of opening, tailings are drawn off with the ore when the latter is drawn off as fast as concentrated on the ore-bed. This is due to the too rapid sinking of the ore in one place; but by a bed constructed as, for instance, in Fig. V a large extent of opening is made practicable, so that though each foot of opening only lets pass a small quantity of ore, yet the sum total of all the openings gives the desired quantity or area, and the speed of the sinking column is so reduced as to prevent the liability of tailings being carried down; also, another advantage is the facility with which the air or water reaches each side of the short columns of ore.

What is here claimed, and desired to be secured by Letters Patent, is—

1. An ore-bed composed of tubes or hollow bars, constructed and arranged to admit of the passage within and through or out of them of a current or currents of air or water, in such manner as that said air or water in escaping therefrom will meet in the center or cross the ore passages or openings in the bed, substantially as specified.

2. An ore-bed made up of tubes of a reticulated character, having an air or water inlet or opening at their end or ends, and made either with or without bottoms *d*, essentially as and for the purpose or purposes herein set forth.

S. R. KROM.
